WINDOW SHADE ATTACHMENT AND SUPPORT

Henry M. Brumser, Portland, Oreg.

Application October 23, 1933, Serial No. 694,799

1 Claim. (Cl. 248—269)

My invention relates to an attaching support and bracket for window shades.

The invention comprises a pair of brackets that are adapted for being fitted to the top of a window sash. A supporting arm outwardly extends from each of the brackets and the arms are adjustable relative to that of the base bracket to provide means for adjusting the same relative to the various windows and window frames with which the same is to be used.

The primary purpose and object of my invention is to provide a support for window shades so that the shade may be raised and lowered as the top window sash is raised and lowered to thereby provide a window and shade that may be raised and lowered together to facilitate the ventilating and the controlling of light rays within the room.

A still further object of my invention consists in providing a simply constructed device that is relatively cheap in first cost and that may be used in conjunction with shades and shade rollers as are used in the present practice.

A further object of my invention consists in providing a base bracket that is adapted for being secured to the top cross bar of the window sash to thereby prevent the marring of the window frame when the same is attached thereto.

A still further object of my invention consists in providing a support for window shades through the use of which it is possible to use a window shade and roller that is wider than the window opening. This wider shade permits greater privacy in those rooms in which the device is used.

A still further object of my invention consists in providing a support for window shades that permits the top of the window shade to be raised and lowered as the sash is raised and lowered. This is particularly advantageous for use on kitchen windows.

With these and incidental objects in view, the invention consists in certain novel features of construction and combination of parts, the essential elements of which are set forth in the appended claim, and a preferred form of embodiment of which is hereinafter shown with reference to the drawings which accompany and form a part of this specification.

In the drawings:

Fig. 1 is a fragmentary front view of a window and window frame. In this view a pair of my new and improved bracket shade supports are shown in front position.

Fig. 2 is a plan view partially in section of the mechanism illustrated in Fig. 1. This view is

taken on line 2—2 of Fig. 1, looking in the direction indicated.

Fig. 3 is a side view of one of a pair of the brackets.

Fig. 4 is a side view of the other of a pair of the brackets. In this view is shown the means for retaining the shade roller spring core against rotation.

Fig. 5 is a sectional end view of the mechanism illustrated in Fig. 2. This view is taken on line 5—5 of Fig. 2, looking in the direction indicated.

Fig. 6 is a front view of a window opening illustrating one of my new and improved devices in place thereupon and in full raised position.

Fig. 7 is a front view of a window opening illustrating one of my new and improved devices in place and secured to the cross bar of the top sash and illustrates the sash in partially lowered position and the shade as being partially drawn.

Fig. 8 illustrates one of my new and improved devices shown attached to the cross bar of the top sash of the window and illustrates the top cross bar of the top window sash in full lowered position.

Fig. 9 is a front view of a window opening illustrating one of my new and improved devices shown attached to the top cross bar of the top window sash and illustrating the sash as being partially lowered and the shade as being drawn all the way down.

Fig. 10 is a front view of a window frame illustrating one of my new and improved devices as being attached to the top cross bar of the top window sash. In this view the top window sash is shown partially lowered and the bottom window as being partly raised and illustrating the shade drawn to the bottom cross bar of the bottom sash.

Fig. 11 is a fragmentary front view of a window frame illustrating one of my new and improved devices attached to the top cross bar of the top sash and illustrating the top sash as being fully lowered and illustrating the shade as being fully raised.

Like reference characters refer to like parts throughout the several views.

I have here shown my device as being attached to a window, the opening of the window being framed in the usual manner with window opening trim. The window comprises a top sash 1 and a bottom sash 2. The top window sash 1 has a top cross bar 3 to which I attach my device.

I comprise my device of a pair of base brackets 4 and 5. These base brackets are comprised of

the base and forwardly extending supports 6 and 7. The base portion of the bracket has holes disposed therein for the reception of a pair of screws 8 and 9 adjacent its top. I place a slot 5 10 adjacent the bottom of the base bracket and through this I place a fastening screw 11. The outwardly extending top parts of the base brackets have channel ways 12 disposed centrally thereof and longitudinally of the top side. Slots 10 13 are disposed centrally of the channel ways. Roller supporting arms 14 and 14A are adapted to the supports 6 and 7 of the base brackets 4 and 5 and slots 15 and 15A are disposed centrally of the support engaging portions of the 15 arms 14 and 14A respectively. The side walls 16 and 17 of the support engaging portions of the arms 14 and 14A permit a close sliding working relationship between the respective members by engaging the side walls of the channel way 12. The positioning of the respective members and the clamping of the same together in desired placement is accomplished through the use of bolts 18 and wing nuts 19. Heretofore window shades have been secured to the frame of the 25 window and unless the window shade is precisely positioned "Peeping Toms" can see between the edges of the shade and the edges of the window frame.

I provide supporting arms 20 and 20A that are 30 formed integral with and disposed at right angles to the arms 14 and 14A and I form downwardly extending terminals 21 and 21A at right angles to the outer end of the supporting arms 20 and 20A. In terminal 21 I form a supporting locking slot 22 into which an end 23 of a shade roller is positioned and retained against rotation. In terminal 21A I place a hole into which the end 23A of the shade roller is rotatably positioned. Horizontal portion 24 of the outwardly extending arms is formed into a segmental arc to increase the strength of the same. The arms are of sufficient length to place the ends of the shade and the shade roller well past the window opening to thereby prevent any possibility of inspection of the room from without when the shade is fully drawn.

In the custom now in general use, the lower sash of the window is raised and lowered for 35 ventilating purposes but best efficiency is accomplished by the raising and lowering of the top sash of the window. The raising and lowering of the top sash is not practicable, at the present time, unless the window shade is fully raised. By the securing of my device to the top cross bar 50 of the top sash it is now possible to raise and lower the top sash for ventilating purposes and for the admission of light, for in so doing the window shade is raised and lowered also. This prevents the whipping of the shade when the top 55 sash is lowered.

To further increase the general utility of my device I place, in supports 6 and 7, a pair of complementary shade supporting apertures 25 and 26, enabling them to be utilized as shade roller brackets in the conventional manner.

In Fig. 6 I have illustrated the top sash as being fully raised and the bottom sash as being fully lowered, and have shown the shade, secured to the top cross bar of the top sash, as in fully raised position for the admission of light through the glass of both sashes. 5

In Fig. 7 I have shown the top sash as being partially lowered to facilitate the free passage of air through an opening 27 disposed between the top cross bar of the top sash and the bottom 10 of the top rail of the window frame. In this view the shade 28 is shown as being partially lowered.

In Fig. 8 I have shown the top sash as being fully lowered and I have also shown the shade 15 as being fully drawn. This permits a free passage of air through the opening 29 and also illustrates the shade as being fully drawn to prevent a view of the room from the exterior below the top sash. 20

In Fig. 9 I have illustrated the top sash as being partially lowered and the shade as fully lowered. This permits a partial ventilation of the room and a full shading of the glass of both the top and bottom sash. 25

In Fig. 10 I have shown the top sash as being partially lowered and the bottom sash as being partially raised and illustrates the shade as being drawn to the bottom cross bar of the bottom sash. This permits a circulation of air through both 30 the bottom and top of the window opening, the free circulation being governed by the partial lowering of the top sash and the partial raising of the bottom sash.

In Fig. 11 I have shown the top sash as being 35 fully lowered and illustrating the bottom sash in its normal lowered position and the shade as being fully raised.

While the form of mechanism herein shown and described is admirably adapted to fulfill the 40 objects primarily stated it is to be understood that it is not intended to confine the invention to the embodiment herein shown and described, as it is susceptible of embodiment in various forms, all coming within the scope of the claim 45 which follows.

What I claim is:

An adjustable window shade support comprising a pair of base brackets secured to the top cross bar of a window sash and each bracket having an arm outwardly extending from the cross bar, and a channel-way formed longitudinally of the arm, an angle arm secured to each channeled arm of the base bracket and adjustable longitudinally thereof, means for preventing rotation of the arms relative to each other, said means comprising elements depending from the angle arm that engage with the side walls of the channel-way, said arm that is angularly disposed to the channel engaging arm being arcuate 60 in lateral cross section and means for securing a window shade roller to the angle arm, said means comprising a leg downwardly extending from the outer end of the angle arm.

HENRY M. BRUMSER. 65
